UNITED STATES PATENT OFFICE.

ROBERT P. SWEENEY, OF UNION, SOUTH CAROLINA.

AIR-INDUCTION CLEANING APPARATUS.

1,426,518.

Specification of Letters Patent. Patented Aug. 22, 1922.

Application filed August 18, 1921. Serial No. 493,260.

To all whom it may concern:

Be it known that I, ROBERT P. SWEENEY, a citizen of the United States, residing at Union, in the county of Union and State of 5 South Carolina, have invented certain new and useful Improvements in Air-Induction Cleaning Apparatus; and I do hereby declare the following to be a full, clear, and exact description of the invention, such as 10 will enable others skilled in the art to which it appertains to make and use the same.

The present invention relates to improvements in air induction cleaning apparatus, and has for an object to provide an improved apparatus for the cleaning and removal of cotton, dust and refuse that collects on and under machinery, on floors, walls, ceilings, etc., in textile mills, but of course it will be understood that the invention 15 may be used for numerous other purposes, and in general wherever a device of this kind is found to be applicable.

An object of the invention resides in so constructing and designing the air induction 20 chamber as to insure a direct and unobstructed passage of the material from the intake nozzle to the collector or receiver.

At the present time apparatus of this character always contains an induction nozzle or air jet which is placed in and obstructs the passage leading from the intake nozzle to the collector or receiver. This seriously interferes with the easy passage of the collected material which thus tends to accumulate about the induction nozzle or jet and to clog the passage and also seriously limit 35 the quantity and character of the material being handled, thereby requiring a useless amount of power.

40 The invention aims to obviate the above difficulties with present apparatus by the production of a simple and inexpensive device hereinafter more fully described.

With the foregoing and other objects in 45 view, the invention will be more fully described hereinafter, and will be more particularly pointed out in the claims appended hereto.

In the drawings, wherein like symbols 50 refer to like or corresponding parts throughout the several views,

Fig. 1 is a side view with parts shown in section of an improved portable apparatus constructed according to the present invention;

Fig. 2 is a top plan view thereof with a portion of the apparatus shown in section on the line 2—2 in Fig. 1;

Fig. 3 is an enlarged fragmentary view of the induction chamber and nozzle; 60

Fig. 4 is a sectional view on the line 4—4 in Fig. 3;

Fig. 5 is a similar view taken on the line 5—5 in Fig. 3;

Fig. 6 is a transverse sectional view taken 65 on the line 6—6 in Fig. 3;

Fig. 7 is a like view on the line 7—7 also in Fig. 3;

Fig. 8 is an end view taken from the right 70 of Fig. 3;

Fig. 9 is a vertical sectional view with parts shown in elevation of a slightly modified form of apparatus;

Fig. 10 is a top plan view of the same;

Fig. 11 is an enlarged side view of the induction chamber and nozzle;

Fig. 12 is a sectional view taken on the line 12—12 in Fig. 11;

Fig. 13 is also a sectional view taken on the line 13—13 in Fig. 11;

Fig. 14 is a similar view taken on the line 14—14 in Fig. 11;

Fig. 15 is an end view of the device shown in Fig. 11; and

Fig. 16 is a horizontal sectional view taken 85 on the line 16—16 in Fig. 9.

Referring more particularly to the drawings, and for the present to sheet 1, 1 designates a portable cabinet mounted for movement upon the rollers 2 and having installed 90 thereupon a fan or blower 3 driven by an electric, gas or other motor 4, the shaft 5 of which is extended to the shaft of the blower 3 forming a direct drive therewith. The motor 4 receives current from plug and

socket connections or through other well-known sources. An arm 6 projecting from one side of the cabinet 1 constitutes a support for a cylinder 7 having a hopper 8 in its lower portion which projects down inwardly into a flexible bag 9 held suspended from the lower end of the cylinder 7. In accordance with a preferred construction the lower edge portion of the cylinder is rolled 95 outwardly and provided with a bead 10, and the upper edge 11 of the sack is equipped with a draw string whereby it may be pulled tightly about the cylinder 7 and be supported from the bead 10. An exceedingly appropriate support for the bag is thus pro-

100

105

110

duced and one which will permit of the bag being readily attached and removed.

The hopper 8 is provided with a gate or valve 12 which is preferably spring closed 5 and opens by weight of the material which accumulates in the hopper 8. The top part of the cylinder is open save for a number of screens 13 which permit of the ascent of the air therethrough but avoid the passage of 10 dust or other particles which are caused to gravitate in the cylinder.

The intake pipe 14 from the blower apparatus is introduced tangentially into the cylinder 7, as indicated in Fig. 2, to thereby 15 create a swirling action just below a spiral rib 15 that extends about the walls of the cylinder 7. This spiral rib is preferably inclined downwardly from the outside wall of the cylinder 7 toward the center thereof, as 20 may be most clearly seen in Fig. 1. This formation causes the material to descend and to move circumferentially in the cylinder so that as soon as it loses its buoyancy it may fall into the hopper 8 and thence into 25 the sack or bag 9.

The suction nozzle is indicated at 16 and is carried on the end of a flexible hose 17 which connects with a pipe 18 disposed above the blower casing. The pipe 18 30 merges into a pipe section 19 which is round at its left hand end where it communicates with the pipe 18 and is flat or rectangular in cross section at its opposite end on the line 6-6 in Fig. 3, as clearly represented in Figure 6.

The intermediate portions of the pipe sections 19 are flattened along triangular lines 20, as indicated to best advantage in Fig. 3, so that the development of the 40 pipe section from the round to the rectangular formation progresses gradually throughout its length from the left to the right as shown or in the same direction with the passage of the air current. The pipe section 19 45 extends into and in fact forms a portion of a Venturi tube. The intermediate restricted portion 21 of the Venturi tube is adjacent the pipe section 19 which is made of a restricted cross section where it merges with the portion 21 and is of an enlarged diameter where such pipe section 19 connects with the pipe 18. The pipe section 19 is, in other words, reduced gradually in diameter, and in like manner the pipe section 22 which 55 forms the other portion of the Venturi tube gradually increases in diameter from the left toward the right or from its point of connection with the portion 21 to its free outlet end within the cylinder 7.

60 The restricted portion 21 of the Venturi tube is larger generally as compared to the pipe section 19 in order to accommodate an induction nozzle 23 which lies beneath the pipe 19 and may, for advantages in construction, be soldered or welded thereto or sus-

70 pended therefrom in any desired manner. The pipe section 23 is likewise flattened along the triangular lines 24 so that it is round in cross section, as indicated in Fig. 5, where it connects with the blower 3 and is rectangular or widened out laterally where it connects with the Venturi restricted tube portion 21. The induction nozzle 23 communicates directly with the fan casing 3 and receives the air therefrom and directs it into 75 the restricted portion of the Venturi tube. The various sections of the Venturi tube and its allied pipes are shown in Figs. 4 to 8 inclusive. An advantage of this construction is that the air being introduced at the restricted portion 21 of the Venturi tube creates a great suction at the nozzle 16 and in the hose 17, pipe 18 and pipe section 19, and in this way creates a very strong draft 80 and exercises a relatively great lifting power 85 on the material such as dust, cotton, etc., to which the nozzle 16 is applied.

Moreover the draft of air through the induction nozzle 23 is directed along the base 90 of the Venturi tube 21 and in a widespread jet so that it exercises an unimpeded and uninterrupted influence. It will be noted that the induction tube 23 does not extend into the pipe section 19 nor interrupt the continuity of the flow of the air, nor does it restrict the size of the pipe nor obstruct it in any manner. The widened portion 22 of the Venturi tube will also give free vent for the 95 expansion of the air after passing through the restricted portion 21 and will thereby 100 create a further suction.

The accumulated matter entering the cylinder 7 will separate in the enlarged chamber there provided, the air naturally rising upward will pass out through the screens 13, while the heavier matter, such as 105 cotton, dust, etc., will settle toward the bottom of the chamber 7 in which it will be assisted by the spiral rib 15. As soon as a sufficient amount of matter accumulates in the hopper 8, the gate 12 will open and allow the same to descend in the bag 9. When the bag is full it is removed and the draw string 11 tightened so that it is in condition 110 for shipment or removal, and a subsequent fresh bag may be similarly put in its place.

Referring more particularly to Figs. 9 to 15 inclusive, the apparatus herein shown is substantially the same in many respects as compared with the apparatus already 120 described, except for the fact that legs or standards 25 are provided directly upon the cylinder 7 and the standards carry rollers 26 which come in contact with the supporting surface and serve to suspend 125 the cylinder and the bag 9. A bracket 27 is employed to hold the Venturi tube in conjunction with the cylinder 7 and connected pipe sections. The pipe or induction nozzle 28 is made onto the other parts of 130

the induction chamber 21 and the end is threaded as shown, so that a hose line containing compressed air, which is obtained from some distant and independent source, 5 can be easily screwed on.

In this case, as in the other, the part 18 is rounded, while the pipe section 19 is flattened gradually and assumes, as indicated in Fig. 13, a substantially square 10 cross section. The progressive portions of the Venturi tube are illustrated in Figs. 14 and 15.

It will be understood that the suction produced in an apparatus of this kind is 15 more continuous and less apt to obstruct the passage of the pipe than with apparatus in which the induction nozzle projects at right angles into the pipe and is then turned angularly so as to direct the issuing jet centrally of the pipe and to suck the air in all around the same. The present induction nozzle introduces the air tangentially and causes the suction in the pipe above it in a line parallel therewith and in no wise 20 obstructs the pipe nor any other part of the apparatus.

It is obvious that various changes and modifications may be made in the details of construction and design of the above specifically desired embodiment of this invention without departing from the spirit thereof, such changes and modifications being restricted only by the scope of the 30 following claims.

35 What is claimed is:—

1. In air induction cleaning apparatus, an elongated hollow member of substantially Venturi tube formation, said member having a partition in one end dividing 40 said end into an upper induction chamber and a lower induction nozzle, said chamber and nozzle each being substantially cylindrical in cross section at their outer ends for attachment to pipes and the like, and 45 gradually merging at their inner ends into substantially rectangular cross-section with the partition forming a common relatively broad wall whereby a column of air issuing from the induction nozzle into the member is adapted to contact with the column of 50 air issuing from the induction chamber throughout a relatively wide area for effecting a rapid and forceful feeding of the air

from the induction chamber, substantially as described.

2. In air induction cleaning apparatus, an induction chamber of initially round cross section terminating in a rectangular cross section, an induction nozzle disposed substantially parallel with the chamber and 60 having a common wall therewith and adapted to introduce air thereinto in a substantially flat, wide stream at the rectangular portion thereof, substantially as described.

3. In an induction cleaning apparatus, an induction chamber having a flat inner end adapted to deliver a relatively broad stream of fluid therefrom and an induction nozzle having a relatively broad end opening at said flat inner end of said chamber for delivering the fluid under pressure in a substantially flat wide stream for surface contact throughout a relatively wide area with the stream of fluid issuing from said induction chamber, substantially as described.

4. In air induction cleaning apparatus, a Venturi tube having an inlet end divided into branches individually rounded for attachment to pipes, said branches merging into the Venturi tube with a relatively broad common division wall there between, one of said branches being adapted to receive fluid under pressure for passage through the Venturi tube and adapted to contact with the column of fluid from the other branch throughout a relatively wide area, whereby to effect a forceful suction through said other branch, substantially as described.

5. In an air induction cleaning apparatus, a Venturi tube having an inlet end tapering toward the restricted portion of the Venturi tube and being of smaller diameter as compared with the restricted portion of the tube, said inlet end being rounded at its outer wider portion for attachment to a pipe and having walls flattened along substantially triangular lines for converging said inlet end from a round cross-section to a rectangular cross-section at its 100 more restricted end, and a connection for introducing fluid under pressure to the restricted portion of the Venturi tube alongside the rectangular portion of said inlet end, substantially as described.

ROBERT P. SWEENEY.
